United States Patent Office.

E. SHOPBELL, OF ASHLAND, OHIO.

Letters Patent No. 70,034, dated October 22, 1867.

IMPROVEMENT IN LIFTING-JACK.

The Schedule referred to in these Letters Patent and making part of the same.

TO ALL WHOM IT MAY CONCERN:

Be it known that I, E. SHOPBELL, of Ashland, in the county of Ashland, and State of Ohio, have invented certain new and useful improvements in Lifting-Jacks; and I do hereby declare that the following is a full and complete description of the same, reference being had to the accompanying drawings making part of this specification, in which—

Figure 1 is a side view of the lifting-jack.

Figure 2 is a vertical section.

Like letters of reference refer to like parts in the different views.

In the drawings, A, fig. 1, is a tubular standard, in which the slide B is moved up and down by means of the lever C and pawls D. This slide is furnished with a rack on each side, as shown in fig. 2, the lever C forming an arm on each side of the standard, to which it is pivoted. The pawls D, above referred to, are pivoted, one on each side of the slide, to the lever C, as shown, the upper ends catching in the rack of the slide. These pawls are held in the rack by means of a spring band, B', passing around them. Pivoted to the side of the standard, at a, is a cam, E. b b are points or pins, extending, from the pawls, as represented in fig. 1.

When the jack is to be used, it is placed so that the cap on the end of the slide comes under the axle of the wheel. Then by moving the lever up and down, thus working the pawls in the racks of the slide, it is caused to rise, thus raising the wheel from the ground. As the lever is pushed down, one of the pawls raises the slide, while the other moves down to catch into the notch below. Thus one pawl rises as the other one is moved down, each one alternately raising the slide. When it is desired to lower the slide, the cam E is turned, so that the ends will press against the pins b, referred to, and thus pushing the pawls out of the rack of said slide and allowing it to drop back into said standard.

What I claim as my improvement, and desire to secure by Letters Patent, is—

The perforated tubular standard A, with the pivoted lever C and cam E, in combination with the slide-rack B, pawls D, and spring B', all arranged and operating conjointly, substantially as and for the purpose set forth.

E. SHOPBELL.
